UNITED STATES PATENT OFFICE

CARL L. IPSEN AND JAMES L. MCFARLAND, OF SCHENECTADY, NEW YORK, ASSIGNEES
TO GENERAL ELECTRIC COMPANY, A CORPORATION OF NEW YORK

FURNACE

Application filed November 29, 1927. Serial No. 236,530.

Our invention relates to furnaces, more specifically to furnaces for brazing, annealing and the like, and has for its object the provision of a simple, reliable and efficient 5 furnace of this character.

In one of its aspects our invention relates to furnaces for carrying out certain heating operations for metals, such as brazing and annealing, in an atmosphere of a selected 10 gas, such as hydrogen, which prevents oxidation of the metal during the heating operation.

Our invention in one form comprises a furnace structure providing an elongated, 15 horizontal chamber which is filled with a selected gas and through which the articles to be treated are passed. A portion of this chamber at the inlet end is heated to a suitable temperature, while the remaining portion 20 of the furnace constitutes a cooling chamber in which the temperature of the articles is reduced to such an extent that they may be removed from the furnace and exposed to the air without detrimental oxidation. Suitable elevating means is provided at the ends of the furnace for inserting and removing the charge, and mechanism for moving the charge through the chamber, together with interlocking mechanism 25 between the elevators and the mechanism for moving the charge for assuring a predetermined sequence of operation.

For a more complete understanding of our invention reference should be had to the 30 accompanying drawing in which Fig. 1 is a side elevation view of an electric brazing furnace embodying our invention, the electrical interlocking mechanism being shown diagrammatically; Fig. 2 is an end elevation 35 view partly in section to a larger scale than Fig. 1; Fig. 3 is a sectional view along the line 3—3 of Fig. 1 looking in the direction of the arrows; Fig. 4 is a perspective view of the supporting means for the articles to 40 be brazed; Fig. 5 is a fragmentary view in section showing details of construction; while Figs. 6, 7 and 8 are fragmentary views in section showing details of the actuating motors.

50 Referring to the drawing, in carrying out

our invention in one form, we provide a cylindrical gas-tight steel shell or casing 10 defining an elongated furnace chamber. This shell is mounted on suitable supports, shown as steel columns 11, in a horizontal 55 and elevated position. Inside the shell at the inlet end are top, bottom and side walls 12 made of heat refractory bricks and defining a horizontal heating chamber 13 provided with relatively small inlet and outlet 60 passages 13^a and 13^b at its ends respectively. Suitable heat refractory heat insulating bricks, not shown, are provided also at the end of the shell adjacent the heated portion. This brickwork serves the purpose of heat 65 insulation whereby loss of heat is prevented. The space between the shell and the brick is preferably filled with a suitable powdered heat insulating material 14, such as a diatomaceous earth. Suitable heating means, 70 such as electric heating resistors 15, (Fig. 2) is provided in the heating chamber 13, these resistors being hung on suitable heat refractory electrically insulating projections or supports 16 built in the furnace 75 wall. Terminals for the heating units are brought out for connection to a suitable supply source through openings 17, suitable electrical insulators being provided for the terminals and the openings being sealed 80 around the terminals, as by means of asbestos packing. Inlet and outlet openings 18 and 19 respectively for the charge, are provided in the bottom of the shell at opposite ends thereof. Access may be had to the 85 interior of the shell for repairs, if necessary, through bulkheads 20 provided with removable covers.

The heating portion or chamber 13 and the connecting passages 13^a and 13^b occupy but 90 a small portion of the total length of the furnace. For example, the total length of the furnace, i. e., the total length of the cylindrical shell, may be about sixty feet, of which the heating chamber 13 and passages 95 13^a and 13^b may constitute approximately 15 feet. The remaining portion of the furnace constitutes a cooling chamber, no brick walls being provided in the interior of the shell in this portion. A substantial pro- 100

portion of this cooling chamber, however, is provided with a water jacket. As shown, a second cylindrical shell 21 (Fig. 3) surrounds the shell 10 in spaced relation therewith throughout the cooling portion. This shell 21 is connected at its ends with the shell 10 so as to form tight joints and cooling water 22 is circulated therethrough. At the top, the shell 21 is provided with a longitudinal opening and has its edges turned upward to form a trough-like opening 21^a. Preferably the cooling water is circulated in a direction opposite to the movement of the articles through the furnace. For example, the water may be admitted through an opening 23 at the bottom adjacent the outlet end of the furnace, and discharged through an opening 24 at the top adjacent the heated portion of the furnace. It will be understood that the articles to be heated are inserted into the heating chamber through the inlet opening 18 and moved at a substantially uniform rate through the heating and cooling chambers to the opposite end where they are removed through the outlet opening 19.

For the purpose of facilitating movement of the articles through the furnace, two series 25 and 26 of rollers or wheels are provided. These wheels are secured to the bottom of the furnace chamber, the wheels in each series being in alignment so that in effect two tracks of wheels are formed extending through the chamber. The metal articles 27 to be brazed, shown as an assembly of parts with brazing metal at the joints constituting a portion of an electric refrigerator, are carried on trays or supports 28 (see Fig. 4). These trays are filled with a suitable powdered heat insulating material 29, such as a powdered diatomaceous earth, sometimes known as "Silocel", whereby the wheels are protected by the supports from the high temperatures in the heating chamber. As shown the bottom of the heating chamber is provided with a central, longitudinal recess in which the wheels 25 and 26 in the heating chamber are mounted. This recess is deep enough so that its sides embrace the trays, sufficient clearance with the trays being provided to prevent jamming. This recess in the bottom of the heating chamber is the same width as the passages 13^a and 13^b.

Suitable metallic supporting pins 30 extend upward from the trays and the articles 27 are placed on these pins. By means of the pins, the article is held in spaced relation with the tray and also in spaced relation with bottom of the heating chamber so that the radiation of the heat to the article is not muffled. Furthermore, the increase in temperature of the article is not retarded by conduction of heat therefrom to the tray. It will be observed from Fig. 2 that the

articles move substantially centrally through the heating and cooling chambers. This assures uniform heating of the article so that all parts of the article arrive at the desired brazing temperature at the same time. As shown four pins are provided for each tray and form supports for a single article 27. On the bottom of each tray are ridges or projections forming a groove 32 of sufficient width to receive a roller and a flat bearing ridge 31 which rides on the other set of rollers. The trays are moved through the heating chamber on these rollers one set of which bears on the ridge 31 while the other set runs in the groove 32 whereby the trays are maintained in spaced relation with the walls of the chamber. Preferably, as shown in Fig. 4, the tray is made in two sections, a separate bottom section 28^a being provided on which the ridge 31 and groove 32 are formed. This section 28^a is secured to the tray proper in any suitable manner as by riveting. With this construction the section 28^a is protected from the high temperature in the heating chamber by the heat insulating material in the tray and warping thereby prevented.

Suitable elevating means is provided just below each opening 18 and 19, comprising platforms or elevators 35 and 36, each of which is provided with counterweights. As shown, the platform 35 (Fig. 2) is supported at its ends by means of chains 37 and 38 which pass over sheaves 39 and 40 and are provided at the opposite ends with counterweights which are sufficiently heavy to raise the platform together with its load. The sheaves 39 and 40 are mounted on a shaft 41 to which is secured a sheave 42. A flexible cable 43 is wound up on this sheave 42 when the platform is raised by the counterweights. This cable is attached to the sheave 42 at one end and its opposite end is secured to a suitable motor, such as a piston moving in a cylinder 44. In order to lower the elevator, water or air, preferably air, is supplied under pressure to the cylinder 44 whereby the sheave 42 is rotated against the counterweights so as to lower the platform. The elevator 36 is similarly arranged, and it is operated by means of a motor comprising a piston moving in a cylinder 45.

The elevators 35 and 36 are each provided with sets of rollers 46 similar in size and spacing with the rollers 25 and 26 in the furnace chamber. As shown, two series of four rollers each are provided on each platform. These rollers are mounted in elevated positions on the platform on pins 35^a which extend into the furnace openings and are of such height that when the elevators are raised the rollers 46 are on the same level as the rollers in the furnace, whereby a tray may be pushed from the elevator 35

into the heating chamber, and a tray received from the cooling chamber onto the elevator 36. The trays are pushed through the furnace by means of a hydraulic motor 47 having a pusher piston 48 which extends through an opening in the inlet end of the furnace in a position to engage the trays.

The series of rollers on each elevator are inclined in each case toward the adjacent 10 end of the furnace and stops are provided at these ends of the elevators against which a tray on the elevator comes to rest. This inclined arrangement of the rollers prevents the trays from rolling off the elevators and 15 furthermore assures that the trays will always occupy predetermined positions on the elevators.

The openings 18 and 19 of the furnace are only slightly larger than the trays, sufficient 20 clearance being provided to avoid the possibility of jamming. This is also true of the passages 13^a and 13^b leading to the heating chamber, which passages are only slightly larger in a transverse direction than 25 the trays and the articles carried thereby. Ordinarily, the elevators will remain in raised positions whereby the furnace openings are closed. A depending flange 49 (Fig. 5) is provided around each furnace 30 opening and when the elevators are raised these flanges fit into troughs 50 on the elevators which are filled with suitable powdered heat refractory sealing material, such as sand. This provides for tightly sealing 35 the furnace chamber when the elevators are raised. Preferably also the openings 18 and 19 are each provided with a pair of doors 50^a (Fig. 5) which are hinged at opposite sides of the opening and when lowered 40 come together in the middle so as to close the opening. Each elevator is provided with a metal loop 51 which has its ends secured to the elevator and extends upward embracing the tray and the articles 45 carried by it. As the elevator is raised the upper end of this loop engages the doors and pushes them upward, as indicated in Fig. 5, and when the elevator is lowered the doors are free to close as soon as the loop 51 50 is lowered below the opening.

In order to still further conserve the heat a metallic baffle plate 30^a is secured on each tray so as to extend across the tray in an upward direction. As shown in Fig. 4, this 55 baffle plate is secured to the pins 30 and its upper edge terminates just below the article 27. This baffle plate is of substantially the same width as the tray, and it will be observed that each tray with its article 27 60 and the baffle 30^a substantially closes the passages 13^a and 13^b leading to and from the heating chamber whereby the escape of heat from the heating chamber is prevented to a great extent.

65 Beneath the cylindrical casing 10 are two

parallel series of rollers 52 corresponding with the series of rollers 25 and 26 in the furnace chamber. These rollers are on the same level as the rollers on the elevators when the elevators are in lowered positions, 70 as shown in dotted lines in Fig. 1.

In operation, the heating and cooling chambers are maintained filled with suitable gas, preventing oxidation, such as hydrogen, or a suitable non-explosive mixture of hydrogen and nitrogen, which is admitted through a pipe 53 communicating with the top of the cooling chamber. The trays carrying the articles to be heated are pushed through the furnace in end to end relation by means of the piston 48; the furnace chamber being filled throughout its length with a train of trays in end to end relation, a tray resting on each of the elevators 35 and 36 and both elevators being in raised position, as shown in Fig. 1. Assuming these conditions, after a predetermined period has elapsed, to be determined by test, such as several minutes, the elevator 36 is lowered 80 removing the tray and the article carried by it. This tray is moved by the operator onto the rollers 51 and 52 and the elevator immediately returned to closed position. The pusher motor 47 is then operated to advance the trays in the furnace for a distance 85 equal to or slightly greater than the length of a tray. This pushes the tray at the opposite end of the heating chamber onto the elevator 36 ready to be removed upon the repetition of the cycle of operations after the 90 predetermined period previously referred to has elapsed. It should be noted that the tray is not pushed completely on the elevator 36, the final movement of the tray being completed by the force of gravity due 95 to the inclination of the roller on the elevator. The elevator 35 is then lowered and a tray containing an article to be brazed is moved upon it and the elevator raised.

100 It will be understood that cooling water is circulated through the water jacket during the operation of the furnace. The cooling end is provided with a sighting arrangement 54 comprising a glass or other transparent insert through which the interior of the 105 furnace may be viewed. An electric light is also provided for the interior of the heating chamber. The trays as they are removed from the elevator 36 are pushed on the rollers 51 and 52 to the opposite end 110 of the furnace where they come to rest against a foot pedal operated stop 52^a, the brazed articles being removed from the trays 115 and replaced by articles which are to be treated.

120 It will be noted that the trays with the articles to be heated thereon are passed through the heating and cooling chambers at a substantially uniform rate, and the heating and cooling chambers are so arranged 125 130

that the articles in being passed therethrough at this predetermined uniform rate are first heated to a desired high temperature sufficient to melt the brazing metal and form a brazed joint, and thereafter the articles in passing through the cooling chamber are gradually cooled so that when each reaches the opposite end of the furnace its temperature has been reduced to a predetermined low temperature at which no detrimental oxidation takes place when the article is removed and exposed to the outside air. Since the articles are upheld in spaced relation with the bottom, top and side walls 15 of the heating and cooling chambers, the heating and cooling is effected at a substantially uniform rate throughout the article itself and with great efficiency. With the particular furnace described, the charging 20 mechanism is operated at approximately five minute intervals to remove an article and insert a cold one at the opposite end of the furnace, and the period required in passing an article through the furnace from the inlet 25 opening to the outlet opening is approximately two hours.

In order that the sequence of operations previously described may be assured, interlocking means is provided between the 30 valves controlling the motor cylinders 44, 45 and 47. Referring to Fig. 1, the valve for the pusher cylinder 47 is controlled by a handle 55, the valve for the cylinder 44 is controlled by the handle 56, and the valve 35 for the cylinder 45 is controlled by the handle 57. It will be understood that these handles are secured to the stems of the respective valves. The upper ends of the handles are provided with notches 58, 59 and 60 respectively and latches 61, 62 and 63 are provided which drop into the notches when the handles are in their central positions, as shown in the drawing, whereby the handles are locked. These latches may be 40 lifted by means of operating coils 64, 65 and 66 respectively. Connected in parallel with the coils 64, 65 and 66 are operating coils 67, 68 and 69 which operate when energized to close holding switches 70, 71 45 and 72. Cooperating with the handles are two-way switches 73, 74 and 75 which are normally closed in one position, as indicated in the drawing, and when the handles are moved toward the left, i. e., in a clockwise 50 direction as shown in the drawing, these switches are moved to their opposite positions whereby one circuit is open and another circuit closed. Included in the connections are also push button switches 76 55 and 77, the switch 76 being normally open and the switch 77 being normally closed.

With the connections shown in the drawing, the operation of the system is initiated at the completion of a heating cycle by 60 closing the push button switch 76 whereby

a circuit is closed from the supply source 78 to the operating coil 66, this circuit being from one side of the supply source through the conductor 79, the coil, conductor 80, conductor 81 and the switch 76 back to the other side of the source of supply. The operating coil 66 raises the latch 63. At the same time the coil 69 is energized and the switch 72 thereby closed. This establishes a holding circuit for the coil 66 after the push button 76 is released, this circuit being from the coil 66 through the switch 72, conductor 82, switch 75, conductor 83 and push button 77 back to the opposite side of the supply source. The handle 57 is now moved first toward the right, i. e., in a counter-clockwise direction, to lower the elevator 36 and when the tray on this elevator has been removed the handle 57 is moved to its extreme position to the left, i. e., in a clockwise direction, whereby air pressure is applied to the opposite end of the cylinder 45 and the elevator is raised. At the same time the switch 75 is temporarily moved to its other position whereby the holding circuit for the coil 66 is broken and the latch 63 thereby released. Switch 75 in this position closes the circuit for the operating coil 64 whereby the latch 61 is raised, this circuit being from one side of the supply source through the coil 64, conductors 84 and 85, switch 86, conductor 87, switch 88, conductor 89, conductor 90, switch 75 and thence through conductor 83 and push button switch 77 back to the opposite side of the supply source.

It should be understood that the switches 86 and 88 are controlled by the pistons of the cylinders 45 and 44 respectively so that when the pistons are forced out to raise the elevators, these switches are closed. A similar switch 91 is associated with the pusher motor 47. As shown, the piston rod of this motor is extended through the opposite end of the cylinder from the pusher rod 48 for the purpose of controlling this switch. Switches 86 and 88 are closed when the pistons of the cylinders 45 and 44 are forced out and switch 91 is closed when the pusher rod 48 is retracted.

Continuing with the operation of the furnace, when the elevator 36 has been returned to its raised position the handle 57 is moved back to its mid-position whereby the supply of air is cut off from the cylinder 45 and the handle locked by the latch 63. When the coil 64 was energized to release the handle 55, as previously noted, the coil 67 was at the same time energized whereby the switch 70 was closed. This establishes a holding circuit for the coil 64 independent of switch 75, this circuit leading from one side of the supply source through the coil, switch 70, conductor 92, switch 73 and push button 77 back to the other side of the supply source.

The handle 55 is now moved toward the right to operate the pusher mechanism and when this has been operated the handle is moved to its extreme left position to retract the pusher. At the same time switch 73 is moved from one position to the other whereby the coil 67 is deenergized and the holding circuit for the coil 64 thereby opened whereby the latch 61 is released. With the switch 73 temporarily held in its other position by the handle 55, a circuit is closed for the operating coil 65 by the closing of the switch 91 when the pusher has been retracted. This circuit leads from one side of the supply source through the coil 65, conductor 93, switch 91, conductor 94, switch 73 and the push button switch 77 back to the other side of the supply source. At the same time the coil 68 is energized and the switch 71 thereby closed and a holding circuit thereby established for the coil 65, this circuit being independent of the switch 73. This circuit leads from one side of the supply source through the coils 65 and 68, switch 71, switch 74 to conductor 83 and thence back to the opposite side of the supply source. As soon as the pusher mechanism has been retracted the operator moves the handle 55 back to its mid-position where it is locked by the latch 61.

In the next step the handle 56 is moved toward the right whereby the cylinder 44 is operated to lower the elevator 35 and after the elevator has been lowered and a new tray and charge placed upon it, the handle 56 is moved toward the left to its extreme position to raise the elevator. At the same time the switch 74 is thrown from one position to the other whereby the coils 65 and 68 are de-energized, and upon the closing of the switch 88 by the cylinder 44 when the elevator has been raised a circuit is established for the coil 66. This circuit is from the supply source through the conductor 79, coil 66, conductors 80 and 85, switch 86, conductor 87, switch 88, conductor 89, switch 74 and conductor 83 back to the opposite side of the supply source. At the same time coil 69 is energized and switch 72 thereby closed whereby a holding circuit is established for the coil 66 independently of switch 74, as previously described. When the elevator 35 has been returned to its raised position the handle 56 is returned to its mid-position in which it is locked by the latch 62. After a predetermined heating interval the cycle of operations is repeated as previously described. When it is desired to shut down the furnace the control relays may be de-energized by means of the push button 77.

In order that the operator may know when the pusher mechanism has operated to advance the charge the desired distance, a red signal lamp 95 is provided. This lamp is connected in circuit with a switch 96 which

is closed by the pusher mechanism when it has advanced the charge. A green signal lamp 98 is provided in circuit with a switch 97 which is closed when the pusher has been retracted.

It is contemplated that after the interlocking system has been put in operation by means of the push button 76, this push button will not be used, nor will the push button 77 be used except when the system is to be deenergized. It will be observed that by means of the interlocking arrangement, it is impossible to operate either elevator unless the other elevator is in raised position. This is due to the fact that the operating coil 66 controlling the elevator 36 can not be energized to release the handle 57 until the switch 88 is closed and this switch is closed only when the elevator 35 is in raised position. It will be noted also that the coil 65 controlling the latch for the handle 56 can not be energized unless the switch 86 is closed and this switch is closed only when the elevator 36 is in raised position. Furthermore, it will be observed that the pusher can not be operated until both elevators are in their raised positions for it will be observed that the coil 64 can not be energized unless the switches 86 and 88 are both closed. Also a predetermined sequence of operation is established for it will be observed that the elevator 36 can be operated only after the pusher has been operated, while the pusher mechanism and the elevator 35 can only be operated thereafter in the order mentioned. This interlocking system effectually prevents improper operation of the furnace which would result in delay and perhaps damage to the furnace itself.

Suitable valve means for controlling the hydraulic and air motors is shown diagrammatically in Figs. 6, 7 and 8. This arrangement is shown with reference to the cylinder 45 although it will be understood that the cylinders 44 and 47 will be provided with similar valve means. With the handle 57 in its mid-position, as shown in Fig. 6, the ducts 99 and 100 leading to the ends of the cylinder 45, respectively, are closed as is also the duct 101 leading to a suitable hydraulic or air supply source, as the case may be. The exhaust duct 102 is also closed with the valve in this position. When the handle 57 is moved to the right, as shown in Fig. 7, duct 99 is connected to the exhaust and the duct 100 is connected to the supply source whereby the piston is retracted to lower the elevator. With the handle 57 in its extreme position to the left as indicated in Fig. 8, the duct 101 is connected to the exhaust duct and the duct 99 is connected to the supply duct 101, whereby the piston is forced back to the position shown in Fig. 5 to raise the elevator. The pusher motor 47 is preferably

operated by water pressure in order to obtain more uniform operation of the pusher rod. The elevator motors may be operated by compressed air. The counterweights for the elevators are made heavy enough to raise the elevators with their loads, as previously noted, in order that the elevators may be raised or maintained in raised positions in the event of failure of the air supply for the operating motors.

In some cases it may be found desirable to use pure hydrogen gas or an explosive mixture thereof and under such conditions in the event that it is necessary to cool the furnace quickly as, for example, in case the operation of the furnace must be temporarily interrupted for repairs, the hydrogen gas may be first driven out by a non-explosive gas after which the furnace may be opened to the outside air and cooled rapidly by forcing a current of air through it. Nitrogen gas may be used to displace the hydrogen. The nitrogen gas being heavier than hydrogen, may be admitted through a pipe 103 communicating with the furnace chamber at the bottom thereof, while the hydrogen gas may be allowed to escape at the top through the duct 53. It will be understood that the duct 53 will be disconnected from the source of hydrogen supply by suitable valve means, not shown, and opened to the outside air to allow the escape of hydrogen. The duct 103, it will be understood, is ordinarily closed by a suitable valve, not shown. When it is found that the gas escaping from the duct 53 is non-explosive the furnace can be opened and air admitted for rapid cooling. If desired the nitrogen gas may be admitted at the top through the duct 53 so as to force the hydrogen out through the bottom opening 103. When either method is used the two gases seem to mix to a considerable extent, and it has been found that the hydrogen can be driven out through the bottom opening 103 by admitting the heavier nitrogen gas through the duct 53 at the top.

While we have described our invention as embodied in concrete form and as operating in a specific manner in accordance with the provisions of the patent statutes, it should be understood that we do not limit our invention thereto since various modifications thereof will suggest themselves to those skilled in the art without departing from the spirit of our invention, the scope of which is set forth in the annexed claims.

What we claim as new and desire to secure by Letters Patent of the United States, is:

60. 1. A furnace comprising walls forming an elongated chamber, said walls being provided with inlet and outlet openings in the bottom at opposite ends of said chamber, means for maintaining a selected gas in said chamber, means for heating a portion

of said chamber adjacent said inlet opening, means for cooling another portion of said chamber, supporting means for the articles to be heated, means for passing a train of said articles to be heated through said heating and cooling portions in succession, and walls forming a restricted opening connecting said heating and cooling portions, said openings being substantially closed by said articles and supports in passing therethrough from the heating to the cooling portion so as to prevent the escape of heat from said heating portion. 75

2. A furnace comprising walls forming a horizontal elongated furnace chamber, said walls being provided with inlet and outlet openings in the bottom at opposite ends of said chamber, means for maintaining a selected gas in said chamber, means for heating a portion of said chamber adjacent said inlet opening, means for cooling another portion of said chamber, elevators adjacent said openings, trays for the articles to be heated, means for pushing a train of trays through said chamber, and walls forming a restricted opening connecting said heating and cooling portions, said opening being substantially closed by said articles and trays in passing therethrough from the heating to the cooling portion so as to prevent the escape of heat from said heating portion. 80

3. A furnace comprising walls forming a chamber provided with inlet and outlet openings in the bottom at opposite ends thereof, means for maintaining a selected gas in said chamber, heating means in said chamber, separately movable supports, on which the articles to be treated are held in spaced relation both with respect to said support and the bottom of said chamber whereby the heating and cooling of each article is effected at a substantially uniform rate throughout the article, means for moving a train of supports through said chamber, and means for inserting and removing said supports. 100

4. A furnace comprising walls forming elongated heating and cooling chambers communicating with each other at their ends, heating means in said heating chamber, means for maintaining a selected gas in said chambers, supports on which the articles to be heated are held in spaced relation both with respect to said supports and with the bottom of said heating chamber whereby the heating and cooling of each article is effected at a substantially uniform rate throughout the article, means for moving a train of supports through said heating and cooling chambers in succession, and means for inserting and removing said supports. 115

5. A furnace comprising walls forming an elongated furnace chamber, said walls being provided with inlet and outlet openings in the bottom at opposite ends thereof, heat- 120

- ing means in said chamber, means for maintaining a selected gas in said chamber, elevators adjacent said openings, sealing means for said openings carried by said elevators, trays for the articles to be heated, means on said trays for supporting the articles in spaced relation with the trays, and means for pushing said trays through said chamber.
6. A furnace comprising walls forming a horizontal elongated chamber, said walls being provided with inlet and outlet openings in the bottom at opposite ends of said chamber, heating means for said chamber, cooling means for another portion of said chamber, means for maintaining a selected gas in said chamber, elevators adjacent said openings for inserting and receiving the charge, means for pushing the charge successively through said heated and cooled portions, and interlocking means between said elevators and said pushing means, for establishing a predetermined sequence of operation between them.
7. A furnace comprising walls forming an elongated chamber, said walls being provided with inlet and outlet openings communicating with the bottom of said chamber at each end, heating means in said chamber, elevators associated with said openings for raising and lowering the articles to be heated, a motor for actuating each of said elevators, pusher mechanism for moving the articles through said chamber, a motor for actuating said pusher mechanism, a manually operable control device for each of said motors, and interlocking means between said control devices for preventing the operation thereof except in a predetermined sequence so as to insure a predetermined sequence of operation of said motors.
8. A furnace comprising a furnace structure including walls forming a horizontal, elongated furnace chamber, said walls being provided with inlet and outlet openings in the bottom at opposite ends of said chamber, heating means for a portion of said chamber at one end, cooling means for another portion of said chamber, means for maintaining a selected gas in said chamber, elevators below said openings for raising and lowering the articles to be heated, a motor for actuating each of said elevators, means for pushing said articles through said chamber, a motor for actuating said pusher mechanism, control means for said motors, and interlocking means for said control means for establishing a predetermined sequence of operation of said motors.
9. A furnace comprising walls forming an elongated chamber, said walls being provided with inlet and outlet openings communicating with the bottom of said chamber at opposite ends thereof, heating means for said chamber, elevators below said openings for raising and lowering the articles to be heated, pusher mechanism for moving the articles through said chamber, means for preventing operation of either of said elevators except when the other one is in raised position, and means for preventing operation of said pusher mechanism except when said elevators are in raised positions.
10. A furnace comprising walls forming an elongated chamber, said walls being provided with inlet and outlet openings communicating with the bottom of said chamber at opposite ends thereof, heating means for said chamber, elevators below said openings for raising and lowering the articles to be heated, pusher mechanism for moving the articles through said chamber, and interlocking means between said elevators and said pusher mechanism whereby said outlet elevator can be operated only after said inlet elevator has been operated, said pusher mechanism can be operated only after said outlet elevator has been operated, and said inlet elevator can be operated only after said pusher mechanism has been operated.
11. A furnace comprising walls forming a horizontal, elongated chamber, said walls being provided with inlet and outlet openings at opposite ends of said chamber, heating means in said chamber, two series of wheels forming parallel tracks extending through said chamber, supports for the articles to be heated arranged to be passed through said chamber on said wheels from said inlet opening to said outlet opening, and means provided on said supports operably associated with said wheels for guiding said supports through said chamber.
12. A furnace comprising walls forming a horizontal, elongated heating chamber, means for heating a portion of said chamber, two series of wheels forming parallel tracks extending through said chamber, supports for the articles to be heated arranged to be passed through said chamber on said wheels, said supports being provided with grooves for said wheels whereby the supports are guided through the heating chamber, and heat insulating means for said supports, said supports being of substantially the same width as the heated portion of said chamber whereby said wheels are protected from the heat in the interior of said chamber.
13. A furnace comprising walls forming a horizontal, elongated chamber, said walls being provided with inlet and outlet openings at opposite ends of said chamber, heating means for a portion of said chamber, cooling means for another portion of said chamber, means for maintaining an atmosphere of a selected gas in said chamber, two series of wheels forming parallel tracks extending through said chamber, trays for the articles to be heated arranged to be passed

through said chamber on said wheels, heat insulating means in said trays, said trays being substantially the same width as the heated portion of said chamber whereby the 5 wheels in said heated portion are protected from the heat of the interior thereof.

14. A furnace comprising walls forming a horizontal, elongated heating chamber, said walls being provided with a longitudinal recess in the bottom of said chamber, 10 means for heating said chamber, two series of wheels in said recess forming parallel tracks extending through said chamber, trays for the articles to be heated arranged 15 to be passed through said chamber on said wheels, said trays being provided with grooves for said wheels, and heat insulating means for said trays, said trays being of substantially the same width as said recess 20 whereby said wheels are protected from the heat of said chamber.

15. A furnace comprising walls forming an elongated heating chamber having relatively small inlet and outlet passages connecting therewith, supports for the articles to be heated, means on said supports for supporting the articles to be heated in spaced relation with the supports, baffle members on said supports below said articles having substantially the same width as 25 said supports, and means for moving a train of supports through said passages and heating chamber, said articles, baffle members and supports substantially closing said 30 passages while passing therethrough whereby the escape of heat from said heating chamber is prevented.

16. A furnace comprising walls forming an elongated heating chamber having relatively small inlet and outlet passages connecting with said heating chamber at opposite ends thereof, supports for the articles to be heated, pins on said supports on which the articles to be heated are held above said 40 supports, baffle members on said supports below said articles having substantially the same width as said supports, and means for pushing said supports in end to end relation through said chamber, said inlet and outlet 45 passages being substantially closed by said trays, articles and baffles in passing therethrough whereby the escape of heat from said heating chamber is prevented.

17. A furnace comprising walls forming a heating chamber having relatively small inlet and outlet passages connecting with said heating chamber at opposite ends thereof, walls forming a cooling chamber connected to one of said passages, supports for 50 the articles to be heated, means on said supports for supporting the articles to be heated in spaced relation with said supports, baffle members on said supports below said articles having substantially the same width 55 as said supports, means for maintaining a

selected gas in said heating and cooling chambers, and means for moving said supports through said heating and cooling chambers in succession, said passages being substantially closed by the supports, baffles and articles while passing therethrough whereby loss of heat from said heating chamber is prevented. 70

In witness whereof, we have hereunto set our hands this 28th day of November, 1927. 75

CARL L. IPSEN.
JAMES L. MFARLAND.
